UNITED STATES PATENT OFFICE

146,941

DESIGN FOR A MODEL AIRPLANE

Alfred Julius Klose, Rolling Hills, Calif., assignor
to G. M. Giannini & Co. Inc., New York, N. Y.,
a corporation of New York

Application March 18, 1946, Serial No. 127,619

Term of patent 3½ years

(Cl. D34—15)

To all whom it may concern:

Be it known that I, Alfred J. Klose, a citizen of the United States, residing in the city of Rolling Hills, county of Los Angeles, State of California, have invented a new, original, and ornamental Design for a Model Airplane, of which the following is a specification, reference being had to the accompanying drawings, forming part thereof.

In the drawings:

Fig. 1 is a perspective view showing my new design as it appears from a point to one side and below and forward, and

Fig. 2 is a perspective view showing my new design as it appears from a point located at the opposite side and above and forward.

I claim:

The ornamental design for a model airplane, as shown.

ALFRED JULIUS KLOSE.
